UNITED STATES PATENT OFFICE.

SAMUEL N. CORTHELL, OF QUINCY, ASSIGNOR TO CORTHELL MANUFACTURING COMPANY, OF BOSTON, MASSACHUSETTS.

TOOL FOR FINISHING THE EDGES OF BOOTS AND SHOES.

SPECIFICATION forming part of Letters Patent No. 236,145, dated January 4, 1881.

Application filed July 24, 1880. (No model.)

To all whom it may concern:

Be it known that I, SAMUEL N. CORTHELL, of the town of Quincy, State of Massachusetts, have invented Improvements in Tools for Finishing the Edges of Boots and Shoes, of which the following is a specification.

This invention relates to improvements in tools for finishing the edges of boots and shoes; and the invention will, in connection with the annexed drawings, be herein fully described, and specifically defined in the appended claims.

Figure 1 is a side elevation of a machine having my improved tools thereto applied. Fig. 2 is a detached reverse view, showing the rand-tool and gages as applied to the machine. Fig. 3 is a side elevation of the rand-cutter as viewed from the right in Fig. 1 and left in Fig. 2. Fig. 4 is a detached elevation of the vertical rand-gage as viewed from the left in Fig. 1 and right in Fig. 2. Fig. 5 is a top or plan view of said gage. Fig. 6 is an under-side or inverted-plan view of the horizontal rand-gage. Fig. 7 is a detached elevation, showing the edge-trimmer disk-gage as viewed from the left in Fig. 1, said disk being in part broken away to show the cutter behind it, the vertical gage being also shown in elevation. Fig. 8 is a detached view showing, in partial diametric section, taken through one of its teeth, the edge-cutter and its disk-gage. Fig. 9 is a detached longitudinal section taken through the rand-cutter, and showing its shaft transversely taken away. Fig. 10 is a top or plan view of my vertical edge-cutter gage. Fig. 11 is a detached vertical section, showing a shoe-sole edge as it leaves the pegging-machine and before commencing the finish of the edge. Fig. 12 is a section similar to Fig. 11, but showing the sole-edge as operated upon by the rotary rand-cutter, which latter and its gages are shown in position by dotted lines. Fig. 13 is a section similar to Figs. 11 and 12, but showing the sole-edge as completed by my improved cutter, which latter is shown in position by dotted lines. Fig. 14 is also a section similar to the preceding, but intended for illustration in showing the result of the previous methods and tools used for a similar purpose.

In these views, A represents a frame, which may be of such form and size as will best

adapt it to the conditions and place where it is to be used.

B is an arbor journaled in boxes at the top of the frame, as shown.

C is a pulley secured on arbor B, to receive the belt by which rotary motion is imparted to said arbor and the tools thereon mounted.

At the opposite or left-hand end, Fig. 1, the usual shank-trimming tool a is mounted. This tool constitutes no part of my invention. In said shaft, nearer the journal-bearings, is mounted the cutter b and rand-disks c, which are secured thereon between the fixed collar d and the screw-nut e in the usual manner.

The cutter b is of well-known form and construction, except the narrow groove f, which is cut in its teeth at the intersection of lines g and h, as is plainly shown in the enlarged Fig. 8. The object and office of said groove f will be hereinafter specified.

The disk c is formed with the holes i, which are so arranged therein that when mounted with cutter b on arbor B they are just within the circumferential line described by the lines g of the teeth of the cutter, and are coincident with the open spaces between said teeth, as shown in Fig. 7.

In Figs. 1, 7, and 10 a gage-support, j, is shown, which is secured in position by the cap-screws of the journal-bearing of the frame, or it may be secured to the frame in any desired manner. At the outer end of this support two curved arcs or fingers, k k, are secured by the screw l, which passes through the slots m m, Fig. 10, in said arcs, whereby the same may be so adjusted as to leave a greater or less space between the lower ends of said arcs, in order to allow the teeth of cutter b to extend below the same to the required extent in the finishing of different kinds of boots or shoes.

An arbor, D, is journaled below arbor B in projecting sleeve F of frame A, or its equivalent, and it is provided with pulley E, for the purpose of rotation, and at the opposite enlarged end of said arbor the toothed rand-cutter n and the gage-disk o are secured to said shaft by an axial screw threaded in the arbor, as shown in Fig. 9. Said cutter is shown in plan in Fig. 3, and it is of slightly less diameter than the gage-disk o.

A gage-holder, *p*, is secured to sleeve *F* by the screws *s*, as shown, and so as to be vibrated thereon, in order that the end next to cutter *n*, and in which stem *u* of gage *t* is secured by set-screw *v*, may be raised or lowered, as required. The form of said gage *t* and its relation to arbor *D* are shown in Fig. 4, and said gage may, by means of set-screw *v*, be adjusted at the desired distance from arbor *D*. It may also, by the described vibration of holder *p*, be arranged oblique or parallel thereto.

A gage, *w*, whose face is oblique to the axis of arbor *D*, is horizontally adjustable relatively to cutter *n*, and it is secured to sleeve *F* by screw *y*, which passes through the slot in stock *x*, Fig. 6, such stock being held from rotation on said screw by steady-pins on either side thereof, as shown by dotted lines in Fig. 1.

The operation of said tools is as follows: After the sole 1 and upper 2 of the shoe have been united, as shown in Fig. 11, the next operation is to cut the bevel termed the "rand." (Shown at 3 in Figs. 12, 13, and 14.) Heretofore this has been done by employing disks *o* as a guide, which, being inserted and traveling in the converging space between the sole and upper, thereby operated as a guide; but I adjust the vertical gage *t*, against which the sole-edge bears, at the desired distance from the periphery of cutter *n* to allow said cutter to cut the rand to the required distance from the edge of the sole or width of the surface thereof. I also adjust the gage *w* at such distance from the face of cutter *n* that the thickest soles of a lot or case of boots or shoes (intended to be of uniform thickness at the edge) will pass between such edge and cutter, while, by varying the position or angle of the plane of the thinner soles relatively to the cutter, the desired width of rand may be cut therein without moving gage *w*; or, in other words, when disk *o* served as the guide or gage the rand was cut relatively to the top of the sole, while, by the use of gage *w*, such rand is now cut relatively to the bottom of the sole. In Fig. 7 the position of the shoe sole and upper when the rand is being cut is shown by dotted lines. After the rand has been cut by rotary cutter *n* in the manner described, leaving the sole in the condition shown in Fig. 12, the shoe is then subjected to the action of cutter *b* on shaft *B*, the shoe being held in the hands of the operator, as when cutting the rand, beneath the cutter, and with the edge of the sole resting upon the arc-like fingers *k* *k*, as shown by dotted lines in Fig. 7. As the edge is moved past said cutter the inner face of the perforated disk *c* acts upon the rand and smooths the same by the action thereon of the angles at the orifices of holes *i* in said disk, while the edge 4 of the sole is cut by the line *g* of cut-

ter *d*, and the grooves *f* in said cutter forms and finishes the corner 5, as shown in Fig. 13. 65 Without such groove the corners of the sole will be slightly rounded, instead of presenting the full appearance which said groove causes, and which is regarded as the best style of a finished edge.

In Fig. 14 the lower corner of the sole is shown at 6 with a bevel or short face cut by line *h* of cutter *b*, which would result in case of a sole thicker than those for which cutter *b* was adapted if the rand was cut with disk 75 *o* serving as the guide or gage, instead of gaging from the bottom of the sole with gage *w*, as described.

I am aware that heretofore inventions have been patented for the same purpose, wherein 80 were embodied gages by which to adjust the shoe-sole edge relatively to the cutters, and that the rand guides or gages so employed have been perforated as described, and I make no claim to such perforated rand-guides, or, 85 broadly, to the cutters or gages or parts therewith employed, my invention being confined to the subject-matter defined, set forth, and embraced in the several claims which are appended to or constitute the termination and 90 summing up of the specification, wherein I have set out and described my invention in connection with such other unclaimed parts as were necessary for the proper elucidation of the functions of the said specific devices, 95 which, as above stated, constitute the precise features or substance of my invention, which I hereby seek to protect by Letters Patent.

The gage *w* may be adjustably pivoted to its stock *x* by the pivot 7 in Fig. 1. 100

I claim as my invention—

1. In the rotary cutter *b*, the circumferential groove *f*, formed in the teeth thereof, at the intersection of lines *g* *h*, whereby a full finish is imparted to the sole at the angle 105 thereof, substantially as specified.
2. In combination with the rotary edge-cutter *b*, the gage *k* *k*, to control the depth of cut upon the sole-edge, substantially as specified.
3. In combination with rand-cutter *n*, the 110 gage *w*, pivoted to the holding-stock *x*, and the latter slotted to receive the holding-screw *y*, whereby said gage may be adjusted in its distance from the cutter, and may be vibrated upon its pivot to the desired obliquity, substantially as specified.
4. The combination of arbor *D*, with its rand-cutter *n* and gage-disk *o*, with the gages *t* and *w*, and arbor *B* with its cutter *b* and gage-disk *c*, all substantially as and for the purposes 120 specified.

SAMUEL N. CORTHELL.
